DIFFERENTIAL TEMPERATURE VALVE WITH PRESSURE OVERRIDE

Franklyn Y. Carter, Dearborn, Mich., assignor to Detroit Controls Corporation, Detroit, Mich., a corporation of Michigan

Application March 13, 1951, Serial No. 215,325

7 Claims. (Cl. 236—80)

This invention relates to new and useful improvements in temperature operated valves and more particularly to a differential temperature valve for controlling flow of cooling water to the condenser of a refrigeration system. In many localities economy of cooling water for refrigeration systems is of great importance and it is highly desirable to utilize to the greatest extent the cooling capacity of water which is used to cool refrigeration condensers.

Accordingly, it is one object of this invention to provide a temperature operated valve of new and improved construction.

Another object is to provide a differential temperature operated valve of new and improved construction which is particularly adapted for controlling flow of cooling water to a refrigerant condenser.

Another object is to provide a new and improved differential temperature operated valve having a pressure operated safety means dominating the control of the valve.

Another object is to provide a pilot operated differential temperature valve having a pressure responsive means operable to override the thermal actuator for the pilot valve for safety operation.

Another object is to provide a refrigeration system wherein the flow of cooling water to the condenser is controlled in accord with the heat requirements thereof and the outlet pressure from the compressor.

Another object is to provide a cooling system for a water cooled condenser of a refrigeration system wherein the flow of water is controlled in response to the differential of cooling water temperature at the inlet and outlet of the condenser and the refrigerant pressure on the outlet side of the compressor.

Other objects will become apparent from time to time throughout the specification and claims as hereinafter related.

This invention comprises the new and improved construction and combination of parts which will be more fully described hereinafter and the novelty of which will be particularly pointed out and distinctly claimed.

In the accompanying drawings to be taken as part of this specification there is clearly and fully illustrated a preferred embodiment of this invention in which drawings:

Figure 1 shows in central section this improved control valve and,

Fig. 2 shows diagrammatically a refrigeration system and the manner in which this valve is connected for use therein.

Referring to the drawings by characters of reference and more particularly to Fig. 2 there is shown a refrigeration system having a compressor 1, condenser 2, receiver 3, expansion valve 4 and evaporator 5 connected in series with each other, the evaporator being connected back to the compressor. The condenser 2 is of the water cooled type and is provided with cooling water through inlet and outlet pipes 6 and 7 respectively, cold water flowing in the direction indicated by the directional arrows. Connected in the inlet pipe 6 to the condenser 2 is a temperature operated control valve 8 having temperature responsive bulb elements 9 and 10 responsive to inlet and outlet temperature of cooling water to and from the condenser 2. The valve 8 is also connected by conduit 11 to communicate with high pressure refrigerant leaving the compressor 1 to provide a response by the valve 8 to refrigerant pressure. The valve 8 is set forth in detail in Fig. 1 and its operation in the system will be described

more fully following the detailed description of the valve itself.

Referring to Fig. 1 it is seen that the valve 8 comprises a main valve casing 12 having an inlet 13 and an outlet 14 and having an internal partition 15 providing a valve port 16 and a valve seat 17. The valve casing 12 has a tubular extension 18 having a cylindrical bore or valve chamber 18a in which there is positioned a cylindrical piston or valve actuator 19 operable to have reciprocal movement therein. The piston 19 is provided with a pressure equalizing aperture 19a and has secured at its lower end by a screw 20 a rubber or composition valve member 21 which engages the valve seat 17 when in a closed position. The upper open end of the casing projection 18 is closed by a pilot valve casing 22 which is secured to the casing flange 23 by a plurality of screws 24 only one of which is shown, a sealing gasket 25 being provided to seal against leakage. Within the casing projection 18 there is positioned a spring 26 which abuts the lower wall of the casing 22 at its upper end and the piston at its lower end to urge the piston 19 toward a valve closed position. The pilot casing 22 is hollow and is divided internally into two chambers 27 and 28 by a valve seat member 29. In the bottom wall of the pilot casing 22 there is provided an aperture 30 opening from the chamber 27 into the valve chamber 18a in the valve casing projection 18. From the chamber 28 a passageway 31 extends through the wall of the casing 22 and projection 18 of casing 12 to the outlet side of the main valve casing 12. The valve seat member 29 in the casing 22 has a valve port 32 provided therein which is closed by a pilot valve member 33 in the chamber 27. The valve member 33 is secured to and carried by a guide member 34 of generally rectangular construction which is longitudinally reciprocally movable in the chamber 27. The guide member 34 is of polygonal cross-section to provide a sliding fit in the chamber 27. The chamber 28 is closed at its open end by a threaded plug member 35 having a central passage 36 therethrough and carrying a cup-shaped casing 37 hermetically sealed thereto. The cup-shaped casing 37 has a threaded inlet fitting 38 for connection to the conduit 11 as shown in the system of Fig. 2. Within the cup-shaped casing there is positioned a pressure responsive bellows member 39 secured at one end and hermetically sealed to the plug member 35 and having a disc-shaped head plate 40 at the other end thereof. The bellows head plate 40 is connected to a valve stem 41 for the valve member 33 and is biased to close the valve by a spring 42 compressively positioned between the bellows head plate 40 and the plug member 35. It should be here noted that the stem 41 is not connected to the valve member 33 but is engageable therewith and movable thereto by the bellows plate 40. The valve casing 22 is also provided with an aperture 43 overlying the valve chamber 27. The aperture 43 is closed by an annular supporting member 44 on which there is pivoted as at 45 a lever member 46 having its lower end positioned in an aperture in the guide member 34 for actuation of the valve member 33. The casing 22 is further closed against leakage through the opening 43 by a flexible bellows member 47 which has its lower end secured to the supporting member 44 and its upper end sealed to the lever member 46. There is provided a T-shaped casing 48 which fits around and secures and seals in position the supporting member 44 and is held in position by a plurality of screws or bolts 49. The actuating lever 46 extends into the T-shaped casing 48 and carried on its upper end a thrust transmitting member 50 having oppositely aligned recesses 51 and 52 receiving the pointed ends of thrust rods 53 and 54 respectively. Extending from one leg of the T-shaped casing 48 and threaded carried thereon is a tubular supporting casing 55 carrying on its end a thermostatic power element generally designated 56. The power element 56 comprises a cup-shaped casing 57 having sealed therein a pressure movable bellows 58. The bellows 58 has a cup-shaped end wall 59 in which is secured one end of the thrust rod 53. There is also provided a rod extension from the cup-shaped wall 59 having a head portion 60 cooperable with a smaller inverted cup 61 as a stop member limiting the extent of movement of the bellows 58. The bellows 58 is urged toward a com-

pressed position by a spring 62 within the power element casing 57. A capillary tube 63 opens into and is hermetically sealed in the power element casing 57 and carries on its other end the bulb element 9 shown in Fig. 2. The bulb element 9, capillary tube 63 and the space enclosed between the power element casing 57 and the bellows 58 are filled with a temperature responsive fluid for thermal response. The power element casing 57 also carries a guide ring 64 which guides an enlarged portion of the thrust rod 53 and which carries a plurality of damping springs 65 frictionally engagable with said enlarged rod portion to reduce the response to sudden minor temperature changes. On the other leg of the T-shaped casing 48 there is threaded carry a tubular supporting casing 66 which carries on its end a temperature responsive power element 67. The power element 67 comprises a cup-shaped casing 68 having secured and sealed therein a pressure movable bellows 69 having a cup-shaped end wall 70. The bellows end wall 70 receives and has sealed therein the other end of the thrust rod 54 and has a rod portion extending within the casing 68 having a head portion 71 cooperable with the inverted cup-shaped member 72 as a stop determining the extent of movement of the bellows 69. There is also provided a capillary tubing 73 sealed in and opening through the power element casing 68 and carrying at its other end the temperature responsive bulb element 10 as shown in Fig. 2. The power element 67, capillary tube 73 and bulb element 10 are filled with a temperature responsive fluid for temperature response of this valve. The bellows 69 is urged toward collapsed position by a spring 74 positioned between the power element casing 68 and the bellows end wall 70. The power element supporting casing 66 also carries rigid therewith a cup-shaped supporting wall 75 having a central aperture therethrough through which extends the thrust rod 54. Within the supporting casing 66 and surrounding the thrust rod 54 there is provided a spring 76 seating at one end on the wall 75 and at its other end against a threadedly adjustable abutment member 77 carried on the rod 54. The spring 76 urges the rod 54 in a direction opposing the power element bellows 69. The abutment member 77 is threadedly adjustable along the rod 54 to determine the extent of compression of the spring 76 and the force which is exerted thereby against the rod 54. The supporting casing 66 has an access opening provided therein through a fitting 78 closed by a threaded plug member 79 and providing access to the abutment member 77 for adjustment of the spring 76.

Operation

As is shown in Fig. 2 the valve 8 is connected in the inlet line to the condenser 2 to control flow of cooling water thereto. The valve is arranged to operate on the differential of inlet and outlet temperature of the cooling water flowing to and from the condenser and is controlled by response of the bulb elements 9 and 10 through their power elements 56 and 67 respectively. The pressure responsive bellows 39 is responsive to the pressure on the discharge or outlet side of the compressor 1 through conduit 11 which would be connected to the inlet fitting 38. The valve 8 as connected in the system shown in Fig. 2 has its inlet 13 connected to the source of cooling water and its outlet 14 connected to the condenser 2. The valve as shown in Fig. 1 is a pilot operated valve operated by pressure of the cooling water flowing through the valve. When the pilot valve 33 is in the position shown in Fig. 1 closing the valve port 32, the pressure of water in the inlet to the valve casing 12 and within the tubular casing projection 18 is equalized through the orifice 19 in the valve piston 19 and the spring 26 is thus able to hold the piston 19 in the position shown with the valve disc 21 closing the valve port 16. When the valve member 33 is moved to open the valve port 32 water from within the casing projection 18 and valve piston 19 is able to discharge through the aperture 30, valve port 32, chamber 28 and discharge passageway 31 causing a pressure differential across the piston 19 which will move the piston 19 against the force of the spring 26 and open the valve port 16 for flow of cooling water to the condenser. The pilot valve member 33 which controls the operation of the main valve is operated by the two power elements 56 and 67 and also by the pressure responsive bellows 39. The valve member 33 may be opened by rocking movement of the lever 46 which may be caused by the resultant

force of the two power elements 56 and 67. The power element 67 is arranged for response to high temperature and the power element 56 to low temperature. The spring 76 determines the amount of difference of force exerted by the power elements 56 and 67 required to move the lever 46 to operate the pilot valve 33. If the spring 76 is set to require a temperature difference of say 20° F., then as long as the difference of temperature of cooling water between the inlet and outlet of the condenser exceeds 20° F., the lever 46 will be moved to open the pilot valve 33 and cause the main valve to be opened. Whenever the temperature difference drops below the set value of say 20° F., the power elements 56 and 67 and the springs 76 and 42 will cause the lever 46 to rotate and move the valve member 33 toward a closed position and thus cause the main valve to be closed. The pressure responsive bellows 39 is provided to operate the pilot valve member 33 to cause the same to be opened and permit cooling water to flow to the condenser whenever a predetermined maximum pressure is produced by the compressor 1. Thus, if the temperature difference between the inlet and outlet of the condenser has dropped below 20° F. and the flow of cooling water has been cut off to the condenser, and if an excessive pressure is produced by the compressor 1, the bellows 39 will operate directly on the valve member 33 and override the force of the temperature responsive power elements to cause the valve to open and supply the required cooling water to the condenser. It should be noted that the pressure responsive operation just described will take place every time the valve is opened from a fully closed position since when the valve is fully closed there is no means to produce required temperature differential between the temperature responsive power elements. After the valve is opened it will then operate on temperature differential as described. It should also be noted that by this construction there is herein provided a simple and highly efficient control valve for controlling flow of cooling water to a refrigerant condenser which will respond accurately to the temperature difference across the condenser and thus provide a great economy in the supply of cooling water but at the same time will provide safety of operation by having incorporated therein a pressure responsive override arrangement which will cause the water control valve to be opened whenever an excessive refrigerant line pressure occurs.

Although there has been described herein only one embodiment of the invention, it will be obvious to those skilled in the art that numerous minor changes or colorable variations therefrom might be made without departing from the scope and intent of this invention which is intended to be limited only by the appended claims.

Having thus described the invention, what is claimed and desired to be secured by Letters Patent of the United States is:

1. In a valve of the character described; a main valve casing having an inlet, an outlet, a valve port, and a valve chamber overlying said port; a main valve member movable in said chamber to open and to close said port, a pilot valve casing carried on said main valve casing and closing said valve chamber, means including said valve casings forming a passageway extending from said valve chamber to the outlet of said main casing, a valve seat in said pilot casing forming a valve port controlling said passageway, a pilot valve member movable in said passageway to open and to close said last-named valve port, thermostatic means carried on said pilot casing and connected to and operable to move said pilot valve member, and pressure responsive means carried on said pilot casing and connected to said pilot valve member in opposed relation to said thermostatic means and operable to override the same to open said pilot valve.

2. In a valve of the character described; a main valve casing having an inlet, an outlet, a valve port, and a valve chamber overlying said port; a main valve member movable in said chamber to open and to close said port, a pilot valve casing carried on said main valve casing and closing said valve chamber, means including said valve casings forming a passageway extending from said valve chamber to the outlet of said main casing, a valve seat in said pilot casing forming a valve port controlling said passageway, a pilot valve member movable in said passageway to open and to close said last-named valve port, thermostatic means comprising a pair of thermo-

static power elements carried on said pilot casing and connected to and operable to move said pilot valve member in accord with a temperature differential, and pressure responsive means carried on said pilot casing and connected to said pilot valve member in opposed relation to said thermostatic means and operable upon occurrence of a predetermined pressure to override the same to open said pilot valve.

3. In a valve of the character described; a main valve casing having an inlet, an outlet, a valve port, and a valve chamber overlying said port; a main valve member movable in said chamber to open and to close said port, a pilot valve casing carried on said main valve casing and closing said valve chamber, means including said valve casings forming a passageway extending from said valve chamber to the outlet of said main casing, a valve seat in said pilot casing forming a valve port controlling said passageway, a pilot valve member movable in said passageway to open and to close said last-named valve port, thermostatic means comprising a pair of remote responsive thermostatic power elements carried on said pilot casing and connected to and operable to move said pilot valve member in accord with a predetermined differential of temperature of response, adjustable spring means resisting operation of said thermostatic means and determining the differential required for valve operation, and pressure responsive means carried on said pilot casing and connected to said pilot valve member in opposed relation to said thermostatic means and operable upon occurrence of a predetermined pressure to override the same to open said pilot valve.

4. In a valve of the character described; a main valve casing having an inlet, an outlet, and a valve port; a tubular projection on said casing forming a valve chamber overlying said port, a valve member closing said port and reciprocally guided in said chamber, said valve member being operated by inlet pressure and having a bleed aperture for equalization of pressure, a spring in said chamber urging said valve member toward closed position, a pilot valve casing carried on said main casing and having a valve seat member and valve port dividing the same into first and second chambers, said pilot valve casing having passageways connecting said first chamber with said valve chamber and said second chamber with said main valve outlet, a pilot valve member guided in said first chamber and having a stem extending into said second chamber, said pilot valve casing having an opening overlying said first chamber, a pivot member positioned over said opening, a lever member pivoted on said pivot member and having its lower end engaging said pilot valve member for operation thereof, a flexible bellows member secured to said pivot member and said lever member to seal said first chamber against leakage, a T-shaped casing carried on said pilot valve casing and securing said pivot member in position, fluid expansive power elements carried on opposite legs of said T-shaped casing and having remote responsive bulb elements, said power elements having thrust rods oppositely and operatively engaging said lever member to operate said pilot valve in accordance with the differential of temperature between said power element bulb elements, an adjustably supported spring positioned in opposition to one of said power elements to determine the differential of temperature required for pilot valve operation, a pressure operated bellows closing the end of said second pilot valve chamber and engaging said valve stem, a cup-shaped cover member enclosing with said bellows a pressure responsive chamber and having an inlet fitting, and said bellows being operable in response to predetermined excessive pressure to override the force of said power elements and move said pilot valve member to an open position.

5. In a control valve, a valve casing having a passageway therethrough with a valve port, a valve member in said casing and cooperable with said port, said casing having a wall opening aligned with said port, fluid pressure responsive means closing said opening, a valve stem interconnecting said responsive means and said valve member, said casing having a side wall opening, a lever operatively engaging said valve member and extending through said side wall opening, a housing carried by said

casing and having an opening through which said lever extends, a thrust rod in said housing and engaging said lever, a thermostatic power element carried by said housing and engaging said thrust rod to actuate said valve member, and a cover member enclosing with said responsive means a pressure responsive chamber, said cover member having an inlet opening to said chamber for connecting said chamber to a source of fluid pressure, and said responsive means being operable in response to a predetermined external pressure supplied through said cover member opening to override the force of said power element and move said lever to actuate said valve member.

6. In a control valve, a valve casing having a passageway therethrough with a valve port, a valve member in said casing and cooperable with said port, said casing having a wall opening aligned with said port, fluid pressure responsive means closing said opening, a valve stem interconnecting said responsive means and said valve member, said casing having a side wall opening, a lever operatively engaging said valve member and extending through said side wall opening, a housing carried by said casing and having an opening through which said lever extends, a pair of thrust rods in said housing engaging said lever in opposed relation, a pair of remote responsive power elements carried by said housing and engaging said thrust rods to actuate said valve member, adjustable spring means cooperable with one of said power elements to determine the condition of said power elements required to open said valve, and a cover member enclosing with said responsive means a pressure responsive chamber, said cover member having an inlet opening to said chamber for connecting said chamber to a source of fluid pressure, and said responsive means being operable in response to a predetermined external pressure supplied through said cover member opening to override the force of said power elements and move said lever to actuate said valve member.

7. In a control valve, a valve casing having an inlet and an outlet and a valve port therebetween, a valve member guided in said casing for movement relative to said valve port, said casing having an opening adjacent said valve member, a pivot member positioned over said opening and supported on said casing, a lever member pivoted on said pivot member and having one end engaging said valve member for operation thereof, a flexible bellows member secured to said pivot member and said lever member to seal said opening against leakage, a T-shaped casing carried on said valve casing and securing said pivot member in position, fluid expansive power elements carried in opposite legs of said T-shaped casing and having remote responsive bulb elements, said power elements having thrust rods oppositely engaging the other end of said lever member and operable to move the same according to the differential of temperature between said bulb elements, an adjustably supported spring in said T-shaped casing positioned in opposition to one of said power elements to determine the differential of temperature required to move said lever, said casing having a second opening on the opposite side of said valve port from said valve member and aligned therewith, a pressure bellows closing said second opening, a valve stem interconnecting said bellows and said valve member, a cup shaped cover member enclosing with said bellows a pressure responsive chamber and having an inlet opening, and said bellows being operable in response to a predetermined excessive pressure to override the force of said power elements and move said lever to open said valve.
